CIRCUIT CONTROLLING DEVICE

Lester W. Guin, Mishawaka, and Joseph L. Cissell,
 South Bend, Ind., assignors to South Bend Current Controller Company, South Bend, Ind., a corporation of Indiana

Application September 6, 1940, Serial No. 355,634

5 Claims. (Cl. 171—97)

This invention relates to circuit controlling devices and more particularly to controlling devices for controlling circuits from a central point.

One of the objects of the invention is to provide a circuit controlling device in which no external control circuits are needed but in which the main power circuit itself operates the controlling device.

Another object of the invention is to provide a circuit controlling device operated from the main power circuit in which the possibility of improper operation due to unintentional interruptions in the power circuit is minimized. According to one important feature of the invention the control device will reset itself if it should be improperly or accidentally operated.

The invention is particularly useful in connection with street lighting systems or the like in which it is desired that all of the lamps shall operate part of the time, for example from dark to midnight, and thereafter only a portion of the lamps shall operate. With the present invention the desired number of lights can be turned out merely by temporarily interrupting the power circuit and at the same time the possibility of accidentally turning out the lights due to unintended interruptions is minimized.

The various objects, advantages and novel features of the invention will be better understood by reference to the following description when read in connection with the accompanying drawings, in which:

Figure 1 is a front elevation of a circuit controlling device embodying the invention;

Figure 2 is a side elevation of Figure 1; and

Figures 3, 4, 5 and 6 are circuit diagrams showing the circuit in different positions.

Referring first to Figure 3 there is shown one type of a standard street lighting circuit in which the present invention has been incorporated. The circuit includes a master switch 10 controlling a high voltage transformer 12 whose secondary is connected in series with a plurality of low voltage insulating transformers 14. A plurality of incandescent lamps 16 are connected respectively to the secondaries of the insulating transformers 14.

The lamps 16 which it is desired shall be energized at all times when the switch 10 is closed are connected directly to the transformers while the others are connected through circuit controlling devices indicated generally at 18. It will be understood that any desired number of lamps may be arranged in a circuit and that any desired

number of the lamps in the circuit may be equipped with the controlling devices 18.

As shown at the right of Figure 3 the controlling device 18 comprises a switch blade 20 movable between two contacts 21 and 22 and connected to one side of the transformer 14 through a heater 23. The contact 21 is connected through a wire 21a to a contact 24 and through a solenoid 25 to a wire 26 leading to the lamp 16. The contact 24 is adapted to be engaged by a switch blade 27 connected by a wire 28 to the blade 20. A second blade 29 movable with but insulated from the blade 27 is connected by a wire 30 to a wire 31 connecting the other side of the transformer 15 to the lamp 16. A contact 32 engageable by the blade 29 is connected by a wire 33 to the contact 22. The double switch blades 27—29 normally are held in the first position shown in Figure 3 by a spring 34 (Figure 2), but are moved to a second position with blade 27 engaging contact 24 by the solenoid 25 when it is energized.

Figures 1 and 2 illustrate one structural arrangement of the parts shown diagrammatically in Figure 3. As shown, the parts are mounted on an insulating panel 35 and may be covered by a suitable cover, not shown. Three contact blocks 36, 37 and 38 are carried by the panel and the power supply lines are connected to the blocks 36 and 37. The lamp 16 is adapted to be connected to the blocks 37 and 38.

From the block 36 a wire 39 leads to one side of the heater 23 which is shown as a flat coil of resistance wire mounted in discs of mica or the like. Adjacent the heater there is mounted a thermostat unit 40 shown as including a stack of annular laminations supporting a snap-action thermostatic disc. Since this unit is of a type in common use and since its detailed construction per se forms no part of the present invention, it is not illustrated in detail. The disc is connected to the switch blade 20 and when cold holds the blade in the position shown, but when heated by the heater 23 snaps to the left to move the blade 20 into engagement with the contact 22.

The double blade 27—29 is pivoted on a bracket 41 and carries an armature 42 aligned with a fixed core 43 around which the coil 25 is mounted. The blade is normally swung to the right as shown by the spring 34 but when the coil 25 is energized it is moved to the left.

When the main switch 10 is closed the circuit will be in the condition shown in Figure 4, energized parts being shown in heavy lines. Since 55 the thermostat 40 is initially cold the blade 20

will be in engagement with contact 21 and a circuit through the lamp 16 will be established from the transformer 14 through wire 39, heater 23, blade 20, contact 21, wire 21a, solenoid 25, wire 26, lamp 16, and wire 31 to the transformer. As soon as the coil 25 is energized the double blade 27-29 will be moved to the position shown in Figure 4 to complete a holding circuit in shunt around the switch 20-21 through wire 28, blade 27 and contact 24.

As soon as the circuits are completed, as described above, the heater 23 is energized and starts to heat the thermostat 40. There will be a time lag after the circuit is completed before sufficient heat is generated to operate the thermostat, and this lag may be made to occupy any desired interval from a few minutes to several hours. Normally it is desirable that the parts be arranged to provide a relatively long lag of an hour or more since during the heating period any temporary interruptions in the power supply will have no effect on the circuit.

When the thermostat 40 becomes sufficiently heated the disc snaps to the left to move the blade 20 out of engagement with contact 21 and into engagement with contact 22, the parts in this position being shown in Figure 5. At this time the lamp 16 is still energized through the holding circuit from the transformer through wire 39, heater 23, wire 28, blade 27, contact 24, coil 25, wire 26, lamp 16, and wire 31 to the transformer. It will be noted that this circuit includes both the heater 23 and the solenoid 25 so that the thermostat will remain heated and the solenoid will continue to be energized to hold the double blade 27-29 in its upper position. This is the position the parts will occupy after the thermostat has been heated and prior to the time when the lamps equipped with controlling devices 18 are to be shut off.

At any desired time when a part of the lamps 16 are to be shut off the main switch 10 may be temporarily opened and closed again. When the switch is opened the solenoid 25 will be de-energized and the double blade 17-29 will fall back to its initial position, as shown in Figure 3, under the influence of the spring 34. Since the interruption is only temporary the thermostat 40 will not have time to cool down and the blade 20 will remain in engagement with the contact 22. The circuit will then be in the condition shown in Figure 6, blade 20 engaging contact 22 and blade 29 engaging contact 32. In this condition the circuit through the lamp 16 is interrupted but a circuit through the heater is maintained from the transformer through wire 39, heater 23, blade 20, contact 22, wire 33, contact 32, blade 29 and wires 30 and 31 to the transformer. This circuit maintains the heater in heated condition to hold the blade 20 in engagement with the contact 22, but cuts out the lamp. Since the heater 23 draws a very low current a substantial saving is affected.

When the circuit is again de-energized for a substantial period of time, as for example when the lights are turned out in the morning, the heater 23 and thermostat 40 will gradually cool down until the blade 20 is moved back to its initial position in engagement with the contact 21. The circuit is thus returned to its starting position, as shown in Figure 3, ready for subsequent operation. In the event that unintended operation should occur after the thermostat has been heated due to accidental interruption of the power circuit, one or more of the controlling devices 18 in 75

different circuits may be operated. However, upon interruption of the circuit for a substantial period of time, as during the daytime, all of the devices will reset themselves as described above so as to be ready for simultaneous operation the following evening.

While one embodiment of the invention has been shown and described in detail it will be understood that this is for purposes of illustration only and is not intended as a definition of the scope of the invention, reference being had for this purpose to the appended claims.

What is claimed is:

1. An electric control circuit comprising a device to be energized connected to one side of an electric circuit, a two-position switch connected to the other side of the circuit and normally lying in one position, a circuit energized by the switch when in said one position to connect said device to said other side of the electric circuit, a solenoid moved by said solenoid when energized from a first position to a second position to complete a holding circuit through the solenoid in parallel with the circuit through the first named switch, delayed action means in circuit with the first named switch for moving the first named switch from its normal position to a second position, and a circuit including said delayed action means, said first switch in its second position and said switch means in its first position to hold the first switch in its second position.

2. An electric control circuit comprising a device to be energized connected to one side of an electric circuit, a two-position switch connected to the other side of the circuit and normally lying in one position, a circuit energized by the switch when in said one position to connect said device to said other side of the electric circuit, a solenoid in said last named circuit, switch means moved by said solenoid when energized from a first position to a second position to complete a holding circuit through the solenoid in parallel with the circuit through the first named switch, a heater in series with said first switch, a thermostat adjacent the heater and connected to the first switch to move it from its normal position to a heated position, and a circuit including the heater, the first switch in its heated position and the switch means in its first position to energize the heater when the solenoid is de-energized with the first switch in its heated position.

3. An electric control circuit comprising a device to be energized connected to one side of an electric circuit, a two-position switch connected to the other side of the circuit and normally lying in one position, a circuit energized by the switch when in said one position to connect said device to said other side of the electric circuit, a solenoid in said last named circuit, a double bladed switch moved by said solenoid when energized from a first position to a second position, one blade of said switch in the second position completing a circuit in shunt across the first named switch, delayed action means in circuit with the first named switch for moving it from its normal position to a second position, and a circuit through the first named switch in its second position and through the other blade of the double-bladed switch in its first position to energize the delayed action means when the solenoid is de-energized.

4. An electric circuit controlling device comprising a two-position switch having a normal position and a second position, a circuit completed

by said switch in its normal position, means in said circuit for establishing a shunt circuit around the switch, delayed action means in said circuit for moving the switch to its second position, and means for establishing a second circuit through the delayed action means and the switch when the circuit is temporarily interrupted with the switch in its second position.

5. An electric circuit controlling device comprising a two-position switch having a normal 10 position and a second position, a circuit com-

pleted by said switch in its normal position, means in said circuit for establishing a shunt circuit around the switch, a heater in series with the switch, a thermostat heated by the heater to move the switch to its second position, and means for establishing a second circuit through the heater and the switch when the first circuit is temporarily interrupted with the switch in its second position.
